LAMP SOCKET

George H. Goble, Haddon Heights, N. J., assignor
to Radio Corporation of America, a corporation
of Delaware

Application October 2, 1946, Serial No. 700,809

4 Claims. (Cl. 173—328)

1

This invention relates to lamp sockets for pre-focused electric lamps and, considered from one aspect, constitutes an improvement upon the invention more broadly claimed in copending application Serial No. 694,038 to Sten E. Bartelson, filed August 30, 1946.

Sockets for pre-focused lamps are usually provided with a plurality of spring-biased pins which engage the base of the lamp and hold it in a position whereat the filament is in register with the optical system which the lamp is designed to serve. The removal of a lamp from such a socket can be an extremely troublesome operation, particularly when the lamp is hot and is mounted in a motion picture projector or other crowded cabinet. Bartelson in his above identified disclosure describes how the foregoing difficulty may be overcome by the provision of a socket containing a movable inner-base to which the spring-biased retaining pins are affixed and by the provision of a lever arm, which extends from said base to the exterior of the socket, for relieving the retaining pins of their clamping action while the lamp is being removed from, or inserted in, the socket.

The present invention is concerned primarily with pre-focused lamp installations of the type wherein it is necessary or expedient to provide the socket not only with lamp-retaining springs but with a plurality of spring-type electrical contacts as well. In applying Bartelson's lever to lamp sockets of this latter type instances have arisen wherein the lamp remained tight in its socket (although relieved of the clamping force of its retaining pins) because no provision was made for relieving the lamp of the retaining force which is applied thereto by the springs on the electrical contacts. In such installations this additional force was found to comprise about 40% of the total retaining force applied to the lamp.

Accordingly, the principal object of the present invention is to provide an improved lamp socket of the type incorporating not only spring-biased lamp-retaining pins, but spring-biased electrical contacts as well, and one characterized by the provision of means for relieving the forces normally exerted upon the lamp by all of said springs, whereby to facilitate the removal or the insertion of the lamp.

The invention will be described in connection with the accompanying drawing wherein:

Fig. 1 is a side elevation partly in section of a pre-focused lamp assembly including a lock socket having a lever actuated releasing mecha-

2

nism constructed in accordance with the principle of the invention.

Fig. 2 is a sectional view taken along the line II—II of Fig. 1.

5 Figs. 3 and 4 are views similar to Fig. 1 but showing the lever in different operating positions and,

Fig. 5 is a sectional view, taken on the line V—V of Fig. 3, of the bottom of the socket of 10 Figs. 1—4, showing details of the spring-actuated electrical contacts for the lamp.

In the drawing, wherein like reference characters are applied to the same parts in all figures, 1 designates generally a casting formed of 15 metal, porcelain or other suitably rigid material which serves as a support for an optical system comprising a lens 2, an electric lamp 3 and a socket 4 which holds the lamp in a position whereat its horizontally disposed filament 5 is 20 in register with the lens 2. The metal base of the lamp is of a conventional type and comprises a dependent tubular portion 6 through the bottom of which its two filament terminals 7 and 7' (see Fig. 5) extend. The lamp base 6 is provided, intermediate its ends, with an outwardly 25 extending circular flange 8 having a number of circumferentially spaced slots 9a, 9b, 9c of tapered width arranged for the reception of a similar number of locking pins 10a, 10b, 10c, 30 which are mounted, in a manner later described, on the socket 4.

The lamp socket comprises an "upper" base in the form of an annular metal disk 11 which is immovably secured to the pedestal 1 and a dependent "lower" base 12 of similar shape which is supported for vertical movement in register with the upper annulus upon the lower ends of the locking pins 10a, 10b and 10c. The said pins 10a etc. extend upwardly through suitably 35 spaced clearance holes in the annulus or disc 11 and terminate thereabove in pinheads which limit the extent of the downward movement of the lower annulus 12. The pins 10a etc. and hence the lower annulus 12 are biased in the 40 downward direction by means of springs 13a, 13b and 13c, which are wrapped, respectively, about the said pins in the space between the upper and lower annular discs. The lower annulus 12 has a dependent integral tubular socket 50 portion 14 which is designed to receive the tubular base 6 of the lamp. This socket portion 14 contains an insulating insert 15 which serves as a bearing for two vertically movable electrical leads 16 and 16' which supply the current to 55 the filament contacts 7 and 7' of the lamp.

lever 21 causes it to pivot about the pin 23 (which movement may cause the arm 24 in which the said pin is supported to swing inwardly, in the direction of the socket) and thereby to act as a lever of the first class. This lever action lifts the lower annulus 12 against the downward biasing force of the springs 13a etc. and raises the heads of the pins 10a etc. out of contact with the lamp-flange 8 so that the lamp 3 can easily be removed from its socket.

5

It will now be apparent that the present invention provides a simple and convenient means for facilitating the removal of a pre-focused lamp from a lock-socket of the type incorporating spring-biased electrical contacts.

15

What is claimed is:

1. In a socket for a lamp having a base provided with an external electrical terminal, an electrical contact mounted for movement on said socket in register with said lamp terminal, a spring for biasing said contact into engagement with said lamp terminal, and a compound lever, operatively connected to said contact and having a lost motion connection with said socket, for moving said contact out of engagement with said lamp terminal against the biasing force of said spring.

2. A socket for a lamp having a base and an electrical terminal on the exterior of said base, said socket comprising a hollow member for the reception of said terminal part of said lamp base,

20

an electrical contact mounted for movement in register with said lamp terminal within said hollow member and extending to the exterior thereof, spring means mounted within said hollow member for biasing said electrical contact into engagement with said lamp terminal, and means

25

including a link member pivotally mounted on said socket, a handle member pivotally connected to said link, and a lever, pivotally connected to

30

said handle, insulated therefrom, and pivotally connected to said contact, for moving said contact out of engagement with said lamp terminal against the biasing force of said spring means.

3. A socket for a lamp having a base, a flange

35

on said base and an electrical terminal on the free end of said base, said socket comprising a socket-base, a plurality of lamp retaining members projecting from said socket base in a position to engage said flange, a sub-base, an electrical contact movably mounted on said sub-base in a position

40

to engage said electrical terminal, and lever means operatively connected to said lamp retaining members and to said electrical contact for moving said lamp retaining members into and out

45

of engagement with said lamp flange and said electrical contact into and out of engagement with said lamp terminal.

4. A socket for a lamp having a base, a flange

50

on said base and an electrical terminal on the free end of said base, said socket comprising an immovable apertured annulus upon which said tube flange is adapted to rest and a vertically movable annulus mounted in spaced relation with respect

55

to said immovable annulus and through which the said free end of said lamp base is adapted to extend, a plurality of lamp-retaining members mounted upon said movable annulus and extending

60

through the apertures in said immovable annulus in a position to engage said flange on said lamp base, spring means for exerting a clamping

65

force upon said lamp flange through said lamp retaining members, an electrical contact for said lamp terminal mounted in said socket and removable with respect to said movable annulus,

70

75

means for biasing said movable electrical contact

These leads 16 and 16' are biased to bear upwardly against the lamp terminals 7 and 7' by springs 17 and 17' which are wrapped, respectively, about the said movable leads.

The lamp 3 is locked in the socket 4 by aligning the bayonet slots 9a etc. in the flange 8 with the retaining pins 10a etc., then entering the dependent tubular portion 6 of the lamp base through the central holes in the upper and lower discs 11 and 12 into the dependent portion 14 of the socket and, finally, twisting the lamp to bring the reduced neck portions of the bayonet slots into register with the pins so that the retaining force of the springs 13a etc. is exerted upon the flange 8 of the lamp and the springs 17 and 17' on the filament leads 16 and 16' exert their force against the electrical terminals 7 and 7' on the bottom of the lamp.

When the lamp 3 and its socket 4 are of the type above described the twisting force required to lock and unlock the lamp must be sufficient to overcome not only the clamping force applied to the tube flange 8 by the spring biased pins 10a etc. but also to overcome the retaining force which is applied to the lamp base 6 through its terminals 7 and 7' by the spring biased electrical contacts 16 and 16'. If the springs, or any of them, are stiff through long non-use, or the lamp bulb is fragile or hot it would be difficult to apply the twisting force required to unseat the lamp.

The foregoing difficulty is overcome, in accordance with the present invention, by the provision of a lever of novel construction which relieves the electrical contacts 7 and 7' (and hence the base 6 of the lamp) as well as the retaining pins 10a etc. (and hence the lamp flange 8) of the forces exerted thereon by the separate groups of spring 13a etc. and 17, 17'.

In the embodiment of the invention which has been selected for illustration there is a short L-shape lever 20 affixed, at the end of the short arm of the L, to the lower end of each of the two electrical leads 16 and 16'. These L-shape members 20 carry a lever 21 which is pivoted on an electrically insulating pin or screw 22 which extends between the said members at the end of the upstanding arm of the L. One end 21a of this lever 21 is free to bear against the underside of the vertically movable lower annulus 12 of the socket and the opposite end 21b or handle of the lever extends a convenient distance beyond the periphery of the socket. There is a hole 21c intermediate the ends 21a, 21b of the lever 21 through which a fulcrum pin or screw 23 extends. This pin 23 is supported upon an arm 24 which, as indicated by the curved arrow in Fig. 3, is pivotally attached to the base of the rigid support or casting 1. It will be observed upon inspection of Fig. 1 that when the lamp 3 is locked in its socket the pin 23 on the pivoted support 24 is not necessarily in contact with the inner surface of the hole 21c in the lever 21.

The action of the above described system of levers is illustrated in Figs. 3 and 4. Thus, referring to Fig. 3, when the free end 21b of the lever 21 is pressed down its opposite end 21a bears against the underside of the annulus 12 and creates an approximately equal and opposite force which is transmitted through the L-shape arms 20 to the lower ends of the movable electrical leads 16 and 16' so that the said leads are pulled downwardly against the force of their biasing springs 17 and 17' and thus release the lower end of the lamp of this source of clamping action. As shown in Fig. 4, further downward movement of the

2,456,501

5

into engagement with said lamp terminal, and lever means operatively connected to said lamp retaining members and to said electrical contact for relieving said lamp-flange and said lamp-terminal of the forces applied thereto by said spring means and said contact-biasing means, whereby to facilitate the removal of said lamp from said socket.
